UNITED STATES PATENT OFFICE

AUGUST VAN DAMME AND HARRY MAENNER, OF ST. LOUIS, MISSOURI

HOT BED

Application filed April 6, 1931. Serial No. 528,118.

This invention relates to a hot bed and has for an important object to provide, in a manner as hereinafter set forth, a device of this character which is particularly adapted 5 for use by small plant growers as a seed germinator and propagating bed.

Other objects of the invention are to provide a hot bed of the aforementioned character which will be simple in construction, 10 strong, durable, efficient and reliable in use, economical to operate and which may be manufactured at low cost.

All of the foregoing and still further objects and advantages of the invention will 15 become apparent from a study of the following specification, taken in connection with the accompanying drawings wherein like characters of reference designate corresponding parts throughout the several views, and 20 wherein:—

Figure 1 is a plan view of a device constructed in accordance with this invention.

Figure 2 is a view in side elevation of the device.

Figure 3 is a detail view partly in elevation and partly in longitudinal section showing a portion of one of the electric heating elements.

Figure 4 is a detail view in perspective 30 showing an end portion of one of the channelled frame members which receive the heating elements.

Figure 5 is a view in vertical cross section 35 through one of the frame members showing the heating elements disposed in position in the channels therein.

Figure 6 is a fragmentary detail view in perspective showing a modified form of the construction of the device.

Figure 7 is a view similar to Figure 6 showing another modification.

Referring to the drawings in detail, it will be seen that the reference numeral 1 designates generally a substantially rectangular, 45 skeleton frame which comprises the outer longitudinal members 2 and 3, the end cross members 4 and 5, the inner cross member 6 which extends between the members 2 and 3 adjacent to and spaced from the end cross member 4 and the inner longitudinal mem-

bers 7 which are disposed in spaced parallelism with each other and which extend between intermediate portions of the end cross member 5 and the intermediate or inner cross member 6. All of the cross members extend 55 between the longitudinal side members 2 and 3, and have their ends rigidly connected thereto in any suitable manner.

The frame 1 is provided with a pair of grooves or channels which begin and end 60 adjacent the center of the end cross member 4 and disposed in said grooves or channels are the heating elements 9, the grooves or channels being designated by the reference numeral 8. Each heating element 9 comprises a resistance wire 10 of suitable gauge 65 which is enclosed in asbestos 11 which, in turn, is enclosed in the metal sheath 12.

A floor flange 13 is mounted on the inner side of the end cross member 4 and has connected thereto one end of a flexible conduit 14 which extends upwardly therefrom and has mounted on its upper end a multiple control switch 15. Conductor wires (not shown) from a suitable source of electric current supply 70 are, of course, connected to the control switch 15 and conductor wires also extend from the switch 15 through the flexible conduit 14 and are electrically connected with the heating elements 9 in the channels 8 of the 80 frame 1.

The frame 1 may be formed from members 16 (see Figure 6) of tubular metal of substantially oval cross section, the heating elements 9 extending through the members 16. 85

In Figure 7 is shown another modified structure from which the frame may be formed. In this form of the invention the members constituting the frame are in the form of inverted channel members 17 of 90 metal formed to provide the spaced, parallel grooves or channels 18 for the reception of the heating elements. The vertical sides of the members 17 are provided with inturned flanges 19 which terminate in upturned lips 95 20 for strengthening the members 17.

In use, the device is placed on the ground and covered with dirt to the desired depth in which the seed is planted. Heat from the elements 9 may then be had to the desired 100

degree through the medium of the control switch 15. The heating elements 9 may be used simultaneously or separately as desired.

It is believed that the many advantages of a device constructed in accordance with this invention will be readily understood, and although the preferred embodiment of the invention is as illustrated and described, it is to be understood that changes in the details of construction may be had which will fall within the scope of the invention as claimed.

What is claimed is:—

1. A device of the character described comprising a horizontally disposed frame of substantially rectangular form and including longitudinal side members, a pair of end cross members, an intermediate cross member, and a pair of intermediate longitudinal members extending between the intermediate cross member and one of the end cross members, all of said members having communicating grooves in their upper sides, electric heating elements disposed in the grooves, means electrically connecting the elements with a source of electric current supply, said means including a control switch.

2. A device of the character described comprising a horizontally disposed skeleton frame formed of inverted channel members, said channel members having their tops formed to provide spaced, parallel, communicating grooves, electric heating elements disposed in the grooves, and means for electrically connecting the heating elements with a source of electric current supply, said means including a control switch.

3. A device of the character described comprising a horizontally disposed skeleton frame formed of inverted channel members, said channel members having their tops formed to provide spaced, parallel, communicating grooves, electric heating elements disposed in the grooves, and means for electrically connecting the heating elements with a source of electric current supply, said means including a control switch, integral, inturned flanges on the free longitudinal edges of the inverted channel members, and upturned lips on the inner edges of the inturned flanges.

4. A device of the character described comprising a substantially rectangular, horizontally disposed skeleton frame, said frame including longitudinal side members and transverse end members extending between the end portions of the side members, the frame further including an intermediate cross member extending between the side members adjacent one of the end members and in spaced, parallel relation thereto, the frame still further including spaced, parallel, longitudinal intermediate members extending between the intermediate cross member and the other end member and disposed inwardly of the side members in spaced parallelism therewith,

electric heating elements extending around the members constituting the frame, and means for connecting the heating elements with a source of electric current supply.

In testimony whereof we affix our signatures.

AUGUST VAN DAMME.
HARRY MAENNER.
